TELEPHONE SYSTEM

Owen Avis Pearce and Idris Trevor Richards,
Liverpool, England, assignors to Associated
Telephone & Telegraph Company, Chicago,
Ill., a corporation of Delaware

Application September 12, 1935, Serial No. 40,200
In Great Britain September 17, 1934

16 Claims. (Cl. 179—27)

The present invention relates to telephone systems and is more particularly concerned with systems in which connections are set up by operators over automatic switches. The invention is particularly applicable to circuits for the setting up of long distance connections and its primary object is to provide improved arrangements for the automatic selection of outgoing lines and for the giving of special indications to the operators in exchanges handling long distance traffic.

According to one feature of the invention, in a telephone system including a group of lines accessible to two different classes of operators in which in the event of all the lines in a desired group being busy a signal is automatically given to the operators when a line in the group becomes idle, arrangements are provided such that if operators in both classes are waiting for an idle line the signal indicating that a line in the group is idle is given only to operators in one class.

According to another feature of the invention, in a telephone system including a group of lines accessible to operators of one class over one group of automatic switches and accessible to operators of another class over another group of automatic switches, in the event of one of said switches finding all the lines in said group busy it establishes connection with call storing apparatus to which it automatically signals the class of operator making the call.

The invention will be better understood from the following description of one method of carrying it into effect, reference being had to the accompanying drawings comprising Figs. 1-15. The circuit drawings should be arranged as shown in Fig. 15 to form the complete circuit.

Fig. 1 shows the trunking arrangement;

Figs. 2, 3 and 4 show a jack-ended first trunk selector accessible only to long distance operators;

Figs. 5 and 6 show a second trunk selector.

Figs. 7 and 8 show the call storing equipment accessible to second trunk selectors.

Figs. 9, 10 and 11 show a key-ended first trunk selector accessible only to demand operators and

Figs. 12, 13 and 14 show the call storing equipment accessible to first trunk selectors.

The trunk selectors are preferably two-directional switches of the type having a so-called rectangular movement in which no release magnet is provided but the restoration of the switch to normal is effected by stepping the wipers forward to the end of the level and then allowing them to complete their restoration by a vertical and rotary movement. A switch of this type is

described in the application of Robert N. Saxby, Serial No. 634,265, filed 22nd September 1932.

Referring now to the trunking diagram of Fig. 1 it will be seen that the first trunk selectors TS1 accessible to the long distance and demand positions designated LD and DM are provided with two sets of wipers and banks, the lower set being allocated to a large group of trunks outgoing to a distant exchange P. This trunk group is reached by transmitting the digit 1 which is absorbed in a switching operation to connect up the lower set of wipers after which the switch releases and performs a level to level hunting operation over the large trunk group. The operator preferably keys up the number into a key sending equipment (not shown) which thereupon sets the automatic switches and during this period the operator is free to attend to other calls.

If all the trunks in the group are busy the wipers rotate on the last level to the 11th step 20 position to connect with the call storing equipment CS1. It will be seen from the drawings that the 11th step multiple between the long distance and demand first trunk selectors is disconnected to provide separate routes of access to the call 25 storing equipment in order to provide the necessary discrimination as will be explained in detail later.

Trunks to other exchanges are reached by transmitting a digit other than 1 as the first 30 digit whereupon a second trunk selector TS2 is taken into use which has access to bothway trunk relay sets BW to the desired exchanges. If the second trunk selector encounters a group busy condition the wipers are rotated to the 11th position where they connect with call storing equipment CS2 similar to that accessible over the first 35 trunk selectors but provided with different supervisory signalling arrangements.

It will first be assumed that a long distance 40 operator wishes to extend a trunk connection to an exchange other than P and for this purpose will insert one of her cord circuit plugs into a jack extending to a first trunk selector, for instance that shown in Figs. 2, 3 and 4. Relay B 45 connected to the sleeve of the jack is operated over the sleeve circuit of the plug thereby at armatures b2 and b3 (Fig. 2) lighting the visual engaged lamps VES around the multiple to inform other operators that this particular circuit 50 is in use, at armature b4 connects earth to conductor 10 extending to a traffic recording meter (not shown) and at armature b5 (Fig. 3) operates relay C. Conveniently the lamps VES are lighted from a low voltage alternating current 55

supply of for example 6 volts. Relay C in operating prepares various circuits and in particular completes a hunting circuit to the sender finder switch SF. If for the purpose of the description it is assumed that the wipers of the sender finder are standing in engagement with contacts extending to a sender which is already in use, wiper P will encounter guarding earth on the contact which is extended through the lower winding of relay K to operate the interrupter relay MC. A parallel circuit may also be traced from earth at armature b_6 through the upper winding of relay K and as a result relay MC operates but, owing to the high resistance of relay MC relay K remains normal. Relay MC at armature mc_1 energizes the driving magnet SFM of the sender finder which upon operation releases relay MC at the contacts s/m and interaction takes place between the two to advance the wipers in search of a free sender. When this is found wiper P will encounter a comparatively low resistance battery which shunts relay MC and relay K thereupon operates over both its windings in series to prevent further hunting. Relay K at armature k_1 opens the circuit to relay MC and completes a holding circuit for itself over its lower winding which is sufficiently low in resistance to mark the selected sender as busy to other sender finders. Relay K also at armature k_5 extends earth over discriminating wiper D to prevent a register controller finder associated with the sender from hunting for a free register controller since this is not required. Furthermore relay K at other armatures not specifically mentioned extends the incoming circuit from the operator through to the storing equipment of the sender and extends the output circuit from the sender to the impulse responding relay A of the trunk selector. During the rotation of the sender finder, relay LP (Figure 2) is intermittently operated from the earthed interrupter cam l_1 and at armature lp_2 short-circuits relay DR thus varying the current in the sleeve circuit and bringing about the flashing of a supervisory lamp in the cord circuit. As soon as relay K switches however, relay A (Fig. 3) is operated in circuit with the sender and in turn operates relay BB which at armature bb_3 opens the flashing circuit to relay LP and the lamp in the cord circuit then shows a steady glow to indicate to the operator that a free sender has been found and that keying may commence.

After keying has taken place, the sender commences to transmit over the negative and positive "out" leads the impulses corresponding to the digits of the number, whereupon relay A (Fig. 3) responds and at armature a_1 repeats the impulses through the low resistance winding of relay C to the vertical magnet VM. Accordingly the vertical magnet raises the wipers to the desired level and on the first vertical step the off-normal springs operate thereby at springs N_1 completing a locking circuit to relay BB and at springs N_4 opening the initial energizing circuit to relay C which remains held over its lower winding in series with the vertical magnet. After the reception of the first digit, relay C releases after its slow period and at armature c_3 completes the following self-interrupter driving circuit to the rotary magnet RM: earth at armature m_3 (Fig. 4), armatures t_1 , b_8 , c_3 and h_1 , off-normal springs N_5 , normal post springs NP_1 , rotary magnet interrupter springs rm , driving magnet RM to battery. The wipers are therefore rotated over the level selected in search of a free outlet

to a second trunk selector and when this is found wiper P_1 encounters idle marking battery whereupon relay T operates quickly over both its windings in series to earth by way of the resistance t_2 in parallel with the upper winding of relay H 5 to cut the driving circuit to the rotary magnet at armature t_1 . At the same time armature t_1 removes the shunt from the upper winding of relay H which thereupon proceeds to operate in series with the rotary magnet and it will be noticed that the earth connection for this circuit is supplied by way of the resistance t_2 in parallel with the lower winding of relay T. Owing to the reversal of the connections the lower winding of relay T now acts in opposition to the upper holding winding but in the circumstances described the holding winding is sufficient to maintain the relay operated in spite of the opposition. If, however, two trunk selectors happen to be testing on to the same outlet simultaneously the current 10 in the upper windings of the respective T relays would then be approximately halved and the opposition winding would in such circumstances be effective in bringing about the release of the relay and cause the switch to step on to the next 15 outlet. This arrangement therefore guards against the dual switching of first trunk selectors on to the same second trunk selector and further, due to inherent differences in the operate and release times of the relays it is clear that one 20 of the switches will take possession of the outlet to the exclusion of the other.

Returning to the operation of relay H, at armature h_3 it opens the circuit to relay T and provides a locking circuit for itself over its lower 25 winding which is sufficiently low in resistance to mark the outlet selected as busy. Further, at armatures h_1 and h_2 the negative and positive lines are extended to the second trunk selector and at armature h_1 the driving circuit is opened 40 to the rotary magnet RM. The sender continues to transmit the remaining digits to set up the succeeding switches and when it has completed its function it releases and in turn disconnects battery from the P wire to release relay K in the 45 first trunk selector. Relay K thereupon at its resting armatures k_2 and k_3 extends the calling circuit over the train of switches set up to the called party and also at the resting armature k_5 completes a self-interrupter homing circuit to the 50 sender finder which rotates its wipers to the home contact.

When the called party replies, battery is connected back over the S_1 wiper to operate relay F (Fig. 4) which at armature f_2 removes a short-circuit from the winding of relay DR thereby reducing the current in the sleeve circuit to extinguish the supervisory lamp in the cord circuit. Conversely, when the called party clears at the end of the conversation, battery is removed 60 from the S_1 wiper so that relay F releases and increases the current in the sleeve circuit to light the supervisory lamp. Relay DR it should be explained enables the operator to control the outgoing relay sets which are locked after the receipt of the clear signal from the distant exchange and also to control the release of the call storer relay set. The foregoing operations will be more fully apparent from the subsequent description.

If, however, all outlets in the level prove busy, the wipers are rotated to the 11th position where the P_1 wiper encounters a battery (not shown) and the selector therefore switches through on to a disconnected outlet. The cam springs are 75

also operated thereby at springs S3 connecting busy tone from lead BT to the upper speaking conductor to inform the operator that the connection is unavailable.

In case any abnormal condition should arise during the homing of the sender, earth is connected to the forced release lead FR which operates relay M. Relay M at armature m1 short-circuits the lower winding of relay K, which thereupon releases, at armature m4 releases relay H and completes a locking circuit for itself, and at armature m5 (Fig. 2) connects number unobtainable tone from conductor NUT to the upper speaking conductor to inform the operator that the connection is unavailable. Under this condition therefore, the first trunk selector only is held and the sender and succeeding switches which may have been taken into use are released.

Upon the release of the connection when the plug is removed from the jack, relay B in the sleeve circuit releases and is followed by relays H and F. A self-interrupter driving circuit is then completed to the rotary magnet from earth connected to conductor 13 via the release signal equipment (not shown) and accordingly the wipers are rotated clear of the banks after which they fall vertically and restore below the banks to the normal condition where the driving circuit is opened at off-normal springs N5. The locking circuit of relay BB is opened at off-normal springs N1 whereupon relay BB releases to restore the switch circuit to its normal condition. To ensure that the long distance operators receive priority over the demand operators it is arranged that the first trunk selector extends a discriminating signal to the second trunk selector. When the switch is stepped off-normal relay LP operates over the off-normal springs N6 and locks to its armature lp1 and later when the switching relay H operates, relay LP is short-circuited by armature h6 and releases. During its release period however, a pulse of positive or booster battery is connected by armature lp3 to the S1 wiper in order to provide the necessary discrimination as will appear from the subsequent description.

When the operator requires a trunk to exchange P she transmits the discriminating digit 1 as the first digit so that the wipers are raised to the first level in which position normal post springs NP1 (Fig. 3) operate to connect relay DA in place of the rotary magnet so that when relay C releases it causes relay DA to operate. Relay DA locks over its left-hand winding and prepares various circuits in connection with the vertical hunting operation which is to follow and at armature da1 completes a driving circuit to the rotary magnet to cause the wipers to restore to normal. When the wipers reach their normal position, relay C is re-operated over the off-normal springs N4 and at armature c9 operates relay DB which locks. Relay DB at armatures db2 to db5 connects up the lower set of wipers db6 completes a self-interrupter driving circuit to the vertical magnet VM as follows: armatures m3, t1, b8, c3, db6, rr2, interrupter springs vm, armatures da2, bb2, c1, lower winding of relay C, winding of vertical magnet VM to battery. Accordingly the switch performs a vertical hunting operation and when a level containing at least one free trunk to an outgoing relay set is found as marked by battery on the appropriate contact of the vertical bank AW, relay T operates over armatures c8 and da6 to

open the magnet circuit and release relay C. Relay C in turn releases relay T and connects it to the P2 wiper over armatures c8, da5 and db4, and at the same time a self-interrupter driving circuit is completed to the rotary magnet RM at armature C3. Accordingly the wipers are rotated over the level selected and when a free outlet is found relays T and H operate in the manner previously explained, this time extending the connection over the lower set of wipers to an outgoing relay set to exchange P. It will be understood that by the provision of normal post springs arranged to be operated on other levels the switch may be caused to perform a similar hunting operation in response to other digits.

If all the outlets are busy the wipers are rotated over the last level selected to the 11th position where relays T and H switch in the manner previously explained to battery on the P2 conductor leading to call storing equipment for example that shown in Figs. 12, 13 and 14. At the same time the cam springs are operated thereby at springs S3 (Fig. 2) extending interrupted number unobtainable tone from conductor INUT to the upper speaking conductor to inform the trunk operator of the busy condition, while at springs S2 (Fig. 4) battery is connected to the negative 2 wiper to operate the call storing equipment as will be explained later. The switch remains in this position and when an outlet to exchange P becomes free, battery is intermittently connected to the S2 wiper from the call storing equipment which intermittently operates relay F and thus causes the supervisory lamp in the cord circuit to flash. When the operator takes up the call, the differential relay DR operates due to the change of current in the sleeve circuit and at armature dr1 connects battery to the S2 wiper to unbalance a differential relay in the call storing equipment which accordingly operates. Earth is then connected back over the positive 2 wiper to operate relay RR which locks, and at armature rr2 releases relay H to institute normal release conditions. When the switch is fully restored relay RR is released at the off normal springs N4 and relay C re-operates to cause the switch to perform a further hunting operation for the free outlet in a manner similar to that already explained.

Referring now to the call storing equipment shown in Figs. 12, 13 and 14, it will be remembered that this is accessible from both the long distance and demand first trunk selectors, the two routes of access being indicated respectively by upper and lower bracketed sets of conductors extending from Fig. 12. When all trunks in the group are engaged earth is removed from the common conductor 14 extending to resting armatures of the guard relays in all bothway trunk circuits and relay GP (Fig. 13) which is normally short-circuited thereby then operates and at its armature gp1 (Fig. 14) lights the trunk congestion lamps TCL around the operator's positions.

If now a long distance operator takes into use a first trunk selector and sets the switch hunting for a free trunk to exchange P the wipers are rotated to the 11th position of the tenth level to connect with the call storing equipment as explained, and relay B (Fig. 12) connected to the P conductor operates in series with the switching relay of the first trunk selector. Relay B prepares various circuits and also at its armatures b2 and b4 (Fig. 12) disconnects the positive and S conductors leading to the demand first trunk selectors to prevent the extension of

the trunk free signal thereto while long distance first trunk selectors are waiting. Further, as a result of the connection of battery to the negative conductor from the cam springs of the trunk selector, the differential relay LC (Fig. 13) is energized over one winding and operates to advance the indicating switch INS (Fig. 14) one step in the following manner: relay LC operates relay R which in turn operates relay V and with both relays R and V operated the magnet INM of the indicating switch is energized. At the end of the magnet stroke the associated interrupter springs *inn* release relay LC which in turn releases relays R and V so that the circuit is opened to the magnet INM which de-energizes and advances the wipers to the second position. In this position wiper IN2 encounters a resistance battery equivalent to that supplied from the first trunk selector and as the differential relay LC is now energized over both its windings with equal current it cannot reoperate. In addition, over wiper IN4 relay A is operated to light the storage lamp SL1 (Fig. 12) and over wiper IN5 relay Y is operated to disconnect the lighting circuit to the storage lamps SL6—SL10. The storage lamps are situated at the supervisor's position and enable her to follow the traffic conditions and to take whatever steps may be necessary to relieve congestion. The function of relays X and Y associated with the bank and wiper IN5 is to economize in the number of relays required for the control of the storage lamps. If a second call is received on the storage group from either a long distance operator or a demand operator a further resistance battery is connected to the negative conductor thus doubling the current flowing through the left-hand winding of the differential relay LC which again operates.

Accordingly the indicating switch INS is advanced to the third position in the manner described where wiper IN2 encounters a resistance battery equivalent to that connected to the negative conductor so that the windings of relay LC again neutralize one another and the relay releases to disconnect the driving circuit; over wiper IN4 relays A and B are now operated in series to light the storage lamps SL1 and SL2. Up to ten calls may be stored in this manner and it will be appreciated that the resistance connections to the bank IN2 and bank IN3 are so arranged to produce one step of the switch INS for each trunk selector connected to the storage equipment. It will also be noticed that relay V is provided with a copper slug to render it slow to release so that it will hold during the stepping of the switch INS to prevent any change in the indicating circuit until the wipers come to rest. It will be seen from reference to the bank and wiper IN5 that after six calls have been stored relay Y is released and relay X operated, the former preparing the lighting circuit to the storage lamps SL6 to SL10 while the latter maintains the lighting circuit to the preceding lamps SL2—SL5 since all the storage relays except A are now released. The multiple contacts of the bank IN1 are led out to terminals 1—10 which may be cross connected as desired to the common set of terminals connecting with relay OFA. The cross connection is chosen arbitrarily and if it is decided that 10 calls shall be stored before delay working commences the cross connection is made to terminal 10. Accordingly when the wipers of the indicating switch come into this position and relay V releases, earth from the congestion control key CCK (assumed to be operated to the automatic

control position) is extended to relay OFA which operates and locks and at armature *ofa2* extinguishes the trunk congestion lamps TCL and lights the delay lamps DL to indicate to the trunk operators that further calls received must now be handled on a delay basis. It will be understood however, that delay working may be commenced at any period at the discretion of the trunk observation operator who can control the lighting circuit of the delay lamps manually by operating the control key CCK to the manual control position shown in the drawings.

When a trunk becomes free, relay GP is short-circuited and released by the re-connection of earth to the common conductor 14 and at its armature *gp4* connects relay LF to earth via the interrupter cam 15. Relay LF therefore intermittently connects battery from the upper winding of relay RR to the S lead to flash the supervisory lamp in the cord circuit in the manner previously explained. The circuit to the lower winding of relay IRR is intermittently interrupted at armature *irr2* but as relay RR is differentially wound it does not operate while both its windings are energized with currents of equal strength. The circuit to the congestion lamps is maintained by relay OFA. When the free trunk is taken up by an operator, battery is connected to the S lead in the trunk selector thereby reducing the current in the upper winding of relay IRR which thereupon becomes unbalanced and operates, and at armature *irr2* opens the circuit to relay LF and at armature *irr1* connects earth to the positive conductor to release the trunk selector in question, after which it performs a further hunting operation in the manner previously described to select the free trunk. Resistance battery on the negative conductor corresponding to this switch is now removed so that the balance of relay LC is again upset and it releases thus causing the indicating switch INS to perform a further hunting operation to a position corresponding to the number of calls still waiting. Relay GP re-operates when earth is removed from conductor 14 to maintain the circuit to the trunk congestion lamps, at armature *gp4* opens a further point in the circuit to relay LF and at armatures *gp2* and *gp3* releases relay IRR.

If it is assumed that both long distance trunk selectors and demand trunk selectors are in engagement with the call storing equipment, it will be seen that so long as relay B remains operated the S lead to the demand trunks selectors is opened and therefore the trunk free flash signal is extended only to long distance operators. When all the long distance trunk selectors have been re-set relay B releases and the flash signal is then extended to the demand operators.

Referring now to the second trunk selector shown in Figs. 5 and 6, when the switch is taken into use relay A operates over the negative and positive conductors and relay B operates over the P wire in series with the switching relay of the first trunk selector. At armature *b5* relay B closes a circuit for a traffic recorder (not shown). Relay A operates relay BB, and relay B at armature *b4* operates relay C, to prepare the circuit for vertical impulsion. In response to the second impulse train, relay A is intermittently operated and at its armature *a1* repeats the impulses through the low resistance upper winding of relay C to the vertical magnet which accordingly raises the wipers to the desired level. On the first vertical step the off-normal springs operate thereby

at springs N2 opening the initial energizing circuit to the lower winding of relay C which however, remains held during impulsive by reason of the copper slug on its core. Relay BB also holds during impulsive. At the end of the impulse train, relay A holds operated and relay C releases after a short period to operate relay E over armature C2 and the off-normal springs N2. Relay E at armature e4 transfers the impulsive circuit to the rotary magnet RM and at armature e7 re-operates relay C which at armature c2 transfers the energizing circuit for relay E to the control of its own armature e1.

If hunting is to take place over the selected level, the digit 1 is then received and repeated through the low resistance winding of relay C to the rotary magnet which advances the wipers into engagement with the first contact of the level selected. Rotary off-normal springs NR2 operate during the first rotary step to open the energizing circuit of relay C so that this relay releases a short period after the end of the impulse and in turn releases relay E. During the slow release period of relay E, relay PS is operated over its lower winding, bank and wiper P, and armatures bt3, c4 and e5 to resistance battery and thereupon locks over its upper winding for the remainder of the connection. Relay PS prepares various circuits which will not be specifically mentioned at this time and completes the following self-interrupter driving circuit to the rotary magnet RM which becomes effective upon the release of relay E: earth at armature h1 (Fig. 6), armature t1, ps2, b1, rr3, c5, ps8, e6, springs N1, interrupter springs rm, winding of rotary magnet to battery. Rotary hunting therefore commences and when a free outlet is found as indicated by marking battery on the P contact, relay T is operated quickly over both its windings in series to earth via the low resistance 16 and at armature t1 opens the driving circuit to the rotary magnet to prevent further movement of the wipers. At the same time armature t1 removes a short-circuit from relay H which proceeds to operate over its upper winding in series with rotary magnet to earth derived from the resistance 16 connected in parallel with the left-hand winding of relay T. The current through the left-hand winding of relay T is reversed under these conditions and the relay performs a dual testing function in the manner described in connection with the first trunk selector. Relay H at armature h6 disconnects relay T and provides a locking circuit for itself over its lower winding which is sufficiently low in resistance to mark the selected outlet as busy. Furthermore, at armatures h1, h2 and h5 the negative, positive and S leads respectively are switched through to the trunk line circuit and the calling operator requests the desired connection from this distant operator.

If all outlets in the level selected are engaged, the wipers rotate to the 11th position where the cam springs operate and at cam springs S3 a resistance battery is connected up to bring about the operation of relay H which switches the calling circuit through to the call storing equipment shown in Figs. 7 and 8. Moreover, at cam springs S2 battery is extended over the S wiper to register the call on the call storing equipment and at springs S4 relay BT is operated. Relay BT at armature b1 (Fig. 5) connects interrupted number unobtainable tone to the upper speaking conductor from conductor INUT and at armature bt3 in conjunction with the cam springs S5

connects relay RS in bridge between the positive wiper and the P wiper.

When a trunk becomes free, alternating current is fed from the call storing equipment over a circuit connected between the positive and P leads and operates relay RS which it will be noted is connected in parallel with a metal rectifier MRB to enable it to hold operated continuously from alternating current. Relay RS at armatures rs1 and rs2 completes circuits for the upper and middle windings of relay RR and at armature rs3 connects relay LF (Fig. 5) to earth by way of the interrupter cam. Relay LF therefore operates intermittently and interrupts the battery connection from relay RR over the S conductor to the first trunk selector where it is repeated to bring about the flashing of the supervisory lamp in the operator's circuit. At the same time the connection to the centre winding of relay RR is also intermittently interrupted and as the relay is differential it does not operate under these conditions. When one of the waiting operators takes up the trunk a further battery connection is made to the S conductor in the first trunk selector, this reduces the current in the upper winding of relay RR whereupon this relay operates, at armature rr4 it releases relay LF and at armature rr2 holds over its lower winding in series with the vertical magnet VM which is also operated. The operation of the vertical magnet unlatches the rotary detent in the manner described in the previously-mentioned Saxby application to allow the wipers to release in a rotary direction only. When the wipers leave the 11th position relay RS releases and when they reach their rotary normal position the normal rotary springs NR1 are again restored and relay RR is released. The rotary hunting is therefore re-commenced and the switch now searches for a free line in the manner already described.

If a particular line in the group is to be selected for example for testing purposes, the corresponding digit is dialled in place of the digit 1 and the wipers move to the required line in the selected level. If the line is free relay H operates during the slow release period of relay E in the following circuit: earth, resistance 16, upper winding of relay H, armatures b1, rr3, c5, ps8 and e2 to resistance battery. Relay H locks over its lower winding and armatures h6, e5, c4 and bt3 to the P wiper to busy the line and complete the connection through to the trunk line circuit. If the line is busy relay H is not operated and upon the release of relay E relay BT operates over armatures ps3, e3, rr2, h4 and b4 to connect busy tone to the upper speaking conductor from conductor BT and intermittent battery to the S conductor extending to the first trunk selector.

In case the switch has been taken into use by a long distance operator the booster pulse on the S conductor which is extended during the switching of the first trunk selector operates relay PF via the metal rectifier MRA and this relay thereupon locks over its right-hand winding. If the call goes on to the call storing equipment the fact that relay PF is operated causes earth to be extended over the negative wiper to operate a discriminating relay in the call storing equipment and at the same time the connections to relay RS are re-arranged.

When a trunk line becomes free the call storing equipment now connects earth to the P wiper alone so that the RS relays are operated in a direct current circuit but only those second trunk selectors which have been taken in use from a

long distance position. Consequently only long distance positions receive the trunk free signal and are thus given preference over the demand positions.

5 Normal post springs NP are provided so that they may be operated on certain levels to cause the switch to rotate automatically after the receipt of the first train of impulses if this condition is required. When these springs are closed 10 relay PS is operated immediately upon the release of relay C and at once institutes the rotary hunting condition.

15 Figs. 7 and 8 show the call storing equipment accessible to second trunk selectors which is similar in operation to the call storing equipment shown in Figs. 12, 13 and 14. Although it has only one route of access it is provided with a discriminating relay PF which operates when a 20 call is extended by a long distance operator to alter the supervisory signalling circuit so that when a trunk becomes free only the long distance operators are signalled as previously explained. When relay PF is normal, as in the case of demand working, the supervisory signal comprises 25 induced alternating current applied between the positive and P conductors. When relay PF is operated as in cases where the call storing equipment has been taken into use by a long distance operator the supervisory signal comprises direct 30 earth connection to the P conductor alone.

35 Figs. 9, 10 and 11 show the first trunk selector accessible from demand positions, this is substantially identical in operation to the first trunk selector of the long distance positions shown in 40 Figs. 2, 3 and 4 except that it is arranged to be taken into use by the operator throwing a key instead of plugging into a jack. It will also be noticed that relay LP has been omitted and there is therefore, no provision for sending a booster signal to the S conductor as in the case of the long 45 distance trunk selector.

Throughout the foregoing circuits the resistance-condenser connections made to relay coils, magnets and across interrupter springs are provided for spark quench purposes.

We claim:

50 1. In a telephone system, a group of lines, means for giving operators of two classes access to said lines, means for storing incompletely connected 55 connections resulting from attempted calls over said lines at a time when the same are all busy, and means responsive to a line becoming idle for transmitting an idle line signal to waiting operators of one class only.

55 2. In a telephone system, a group of lines accessible to two different classes of operators, the means of access including automatic switches adapted to hunt over said group of lines, call storing apparatus with which said switches automatically establish connection responsive to calls for lines in said group when the same are all 60 busy, and means included in said apparatus responsive to a line of said group becoming idle for signalling the fact to the operators of one class to the exclusion of the operators of the other class.

65 3. In a telephone system, a trunk leading from an operator's switchboard to a selector, a group of trunks accessible to said selector, means for operating said selector responsive to a digit transmitted over said first trunk to cause the selector to hunt for an idle trunk in said group, means for holding the incomplete connection if all trunks in said group are found busy, means for transmitting a free signal over said first trunk

70 to the operator when a trunk in said group becomes idle, and means responsive to a control condition imposed on said first trunk by the operator for releasing said selector and for automatically causing the same to rehunt over said 75 group to find the idle trunk.

75 4. In a telephone system, two groups of first selectors for use by two classes of operators, respectively, a group of second selectors accessible to both said groups of first selectors, means in 80 each second selector responsive to selection thereof by a first selector in the group used by a particular class of operators for registering such selection, call storing apparatus accessible to said second selectors if a selected group of trunks 85 is busy, and means in each second selector controlled by said registering means for transmitting to said call storing apparatus a signal indicative of the class of operator engaged in the call.

85 5. In a telephone system, two groups of first selectors for use by two classes of operators, respectively, a group of second selectors accessible to both said groups of first selectors, means in 90 each second selector responsive to selection thereof by a first selector in the group used by a particular class of operators for registering such selection, call storing apparatus accessible to said second selectors if a selected group of trunks 95 is busy, means in each second selector controlled 100 by said registering means for transmitting to said call storing apparatus a signal indicative of the class of operator engaged in the call, means in the call storing apparatus responsive to an ensuing 105 idle trunk condition for sending a free signal of predetermined character to the second 110 selectors connected therewith, and free signal receiving means in each second selector prearranged to respond or not dependent on whether the associated registering means has been operated.

115 6. In a telephone system, first selectors, second selectors, a group of trunks accessible to an operator through said first selectors, a second group of trunks accessible to said operator through said first selectors and second selectors, a call storing apparatus accessible to said first 120 selectors if all trunks of said first group are busy, means in said apparatus for sending a signal to a connected first selector responsive to a trunk in said first group becoming idle, a call storing apparatus accessible to said second selectors if all trunks in said second group are busy, means for sending a signal to a connected second selector from said second apparatus responsive to a trunk in said second group becoming idle, and means in the connected second selector responsive to the signal received from said second storing apparatus for transmitting to the connected first selector a signal identical with the signal which the first selectors receive from said first 125 storing apparatus.

130 7. In a telephone system, selectors for use in common by two classes of operators, a group of trunks accessible to said selectors, call storing apparatus accessible to said selectors if operated at a time when said trunks are all busy, means in each selector effective when in use by a particular class of operator for conditioning itself to receive a particular kind of signal and for indicating to the storing apparatus the kind of signal it is adapted to receive, and means in said storing apparatus responsive to a trunk in said group becoming idle for transmitting to all 135 selectors connected therewith a signal of the character

acter to which the selectors in use by said particular class of operator is adapted to respond, whereby selectors in use by operators of the other class are unaffected.

5. 8. In a telephone system, two groups of automatic switches for use by two classes of operators, respectively, in extending calls to a group of lines, call storing apparatus for holding calls that cannot be completed due to all said lines being busy, 10 and means responsive to a busy condition being encountered on a call by a particular class of operator for transmitting to the storing apparatus an indication of the class of operator making the call.

15. 9. In telephone system, two groups of automatic switches for use by two classes of operators, respectively, in extending calls to a group of lines, call storing apparatus for holding calls that cannot be completed due to all said lines 20 being busy, means responsive to a busy condition being encountered on a call by a particular class of operator for transmitting to the storing apparatus an indication of the class of operator making the call, and means effective upon a line 25 of said group becoming idle and contingent on said class indication having been received for transmitting a free line signal to the waiting operators of said particular class only.

10. In a telephone system, a group of lines, a 30 group of switches having common access to said lines, an overflow trunk accessible in common to said switches if said lines are all busy and adapted to be connected with concurrently by a plurality of said switches, and means controlled over 35 said overflow trunk responsive to successive switches seizing the same or releasing for indicating the number of switches connected therewith at any time.

11. In a telephone system, a group of lines, a 40 group of switches having common access to said lines, an overflow trunk accessible in common to said switches if said lines are all busy, an indicating switch, and means controlled over said overflow trunk for maintaining said indicating 45 switch in a position corresponding to the number of switches of said group that are connected with said overflow trunk.

12. In a telephone system, a group of lines, a group of switches having common access to said 50 lines, an overflow trunk accessible in common to said switches if said lines are all busy, an indicating switch, means controlled over said overflow trunk for maintaining said indicating switch in a position corresponding to the number of switches

of said group that are connected with said overflow trunk, a group of lamps for indicating the degree of occupancy of said overflow trunk to an operator, and means whereby said indicating switch controls said lamps.

5. 13. In a telephone system, a line adapted to be occupied by a random number of calls simultaneously, a switch associated with said line, and a relay jointly controlled over a conductor of said line and the banks of said switch to maintain 10 the switch in the position which corresponds to the number of calls occupying said line.

14. In a telephone system, a line adapted to be occupied by a random number of calls simultaneously, a stepping switch associated with said 15 line, a differential relay, means for stepping said switch responsive to energization of said relay, a circuit for one winding of said relay in which the current flow depends on the number of calls occupying said line, a circuit for the other winding 20 of said relay including the banks of said stepping switch, and bank wiring arranged to vary the current flow in said second circuit in accordance with the position of said switch.

15. In a telephone system, a trunk line, a two motion selector terminating said trunk line and having bank contacts arranged in levels, means for operating said selector in a directive primary movement to select a level and a hunting movement along the selected level or alternatively in 30 a primary movement which is automatically released and in two successive hunting movements over levels and contacts in a selected level, respectively, and means dependent on the value of 35 a digit received over said trunk line for determining whether said first operation or the alternative one takes place responsive to the digit.

16. In a telephone system, a trunk, a selector in which said trunk terminates, said selector having two sets of wipers, a plurality of groups of contact sets accessible to each set of wipers, individual groups of contact sets accessible to one set of wipers, a single large group of trunks assigned to the groups of contact sets accessible to the other set of wipers, means for variably operating said selector by digit impulses transmitted over said first mentioned trunk, means for initiating an automatic hunting operation over the individual trunk group corresponding to the digit received, and means responsive to a particular digit 40 for releasing said selector and for causing it to 45 hunt for an idle trunk in said large group.
